NONREFILLABLE BOTTLE CLOSURE

Tennies F. Kolts, Chicago, Ill., assignor, by
mesne assignments, to Warren Buckley, Chi-
cago, Ill.

Application October 28, 1937, Serial No. 171,429

11 Claims. (Cl. 215—22)

This invention relates to a nonrefillable bottle closure.

This invention is an improvement over the invention shown in my co-pending application 5 Serial No. 145,728, filed June 1, 1937, on a Non-refillable bottle closure.

It is an object of this invention to provide an improved nonrefillable bottle closure which is relatively simple and inexpensive in construction 10 and efficient in use.

Another object of the present invention is to provide a nonrefillable closure for bottles and analogous containers for preventing the fraudulent refilling of bottles, especially liquor bottles, 15 by the methods now in use for effecting such fraudulent refilling and which methods include exhausting the contents of the bottle by means of a vacuum pump and then submerging the exhausted bottle in the liquor with which it is desired to refill the bottle, whereupon, by reason 20 of the vacuum, or partial vacuum, in the bottle the latter will be rapidly refilled with the liquor, thus accomplishing the fraudulent object such as substitution of an inferior quality of liquor or avoiding the payment of internal revenue tax 25 on the same.

It is an important object of the present invention, therefore, to provide a new and improved non-refillable container closure which is especially adapted for use on liquor bottles and the like for preventing fraudulent refilling of the same for the purpose of evading the internal revenue tax thereon or for other fraudulent purposes, such as the substitution of an inferior 30 quality of liquor.

Another object of the present invention is to provide a bottle closure which is nonrefillable by any of the known methods of fraudulently refilling liquor bottles such as the vacuum-submergence method and partial submergence by hand 35 which may be resorted to in an attempt to refill a bottle by partially submerging the same in the liquor or other liquid so as to leave the mouth of the closure partially open for the escape of air from the body of the bottle.

An additional object of the present invention is to provide a new and improved non-refillable bottle closure which is so constructed that it will enable liquid to be poured from the bottle 40 to which it is attached as soon as the bottle is placed or held in horizontal position.

Another object of the present invention is to provide a new and improved non-refillable bottle closure which embodies a ball-actuated valve 45 and a retaining cage for the said ball which is so

constructed that regardless of how slight the angle, at which the neck of the bottle is tilted above the horizontal, may be the ball will act on the valve to close the same as long as the neck of the bottle is inclined very slightly toward the body of the bottle; that is, even though the bottle is held in such a manner that the neck of the same is inclined at only a very slight angle upwardly from the horizontal (and inclined downwardly toward the body of the bottle), the 10 ball will nevertheless operate on the valve to close the same and thus prevent the bottle from being fraudulently refilled by partially submerging the same by hand or otherwise in a body of liquor or other liquid. 15

A further object of the invention is to construct the new nonrefillable bottle closure in such a manner that when the same is in position of use upon the neck of a bottle the latter may be held in such a position that if the neck 20 of the bottle is tilted at only a very slight angle above the horizontal (and inclined downwardly toward the body of the bottle), the bottle may then be rotated through a complete revolution or 360° and the ball will at all times operate on 25 the valve to close the same and thus prevent fraudulent refilling of the bottle by holding the same partially submerged at any point throughout the said revolution or 360°.

Another object of the invention is to construct 30 the new non-refillable bottle closure in such a manner that when it is mounted on the neck of a bottle the main axis and center line of the closure casing and ball-retaining cage will extend at an acute angle relative to the vertical 35 axis and center of the neck of the bottle whereas the main axis and center line of the valve housing and valve will extend parallel to, and will be coincidental with, the main axis and center line of the neck of the bottle. 40

It may be observed, in this connection, that research and investigation have disclosed that in order to refill conventional bottles by submerging the same in a liquid the bottle must be tilted in such a manner that the main axis and center line of the neck of the bottle are at least 12° from the horizontal, that is, downwardly toward the body of the bottle. 45

Another object of the present invention is to construct the closure casing which is embodied in the new closure in such a manner that it will not dribble during the pouring operation, that is, in such a manner that the stream of liquor or other liquid being poured therefrom will pour 50 55

without dribbling, thus preventing loss of the liquid and avoiding spilling of the same.

An additional object of the present invention is to construct one form of the same in such a manner that any possibility of the valve-actuating ball becoming entrapped in its cage, that is, failing to move back into valve-closing position when the bottle to which the closure is attached is tilted upwardly from horizontal, pouring position, is eliminated.

Other objects will appear hereinafter.

The invention consists in the novel combination and arrangement of parts to be hereinafter described and claimed.

15 The invention will be best understood by reference to the accompanying drawing showing the preferred form of construction, and in which:

20 Fig. 1 is a central vertical sectional view showing a preferred form of the new nonrefillable bottle closure attached to the neck of a conventional bottle, only part of which bottle neck is shown, and showing the new closure in the position in which it is arranged when the bottle to which it is attached is in upright or vertical position;

25 Fig. 2 is a central vertical sectional view of the preferred form of the new bottle closure which is shown in Fig. 1 but showing the same in so-called pouring position, that is, with the neck of the bottle in horizontal position and with the valve of the new closure in open position;

30 Fig. 3 is a transverse sectional view, on line 3—3 in Fig. 1, illustrating part of the construction of the valve housing;

35 Fig. 4 is an exploded perspective view showing the various parts which are embodied in the form of the invention which is illustrated in Figs. 1 to 3, inclusive;

40 Fig. 5 is a view similar to Fig. 1 but illustrating a modified form of the invention; and

45 Fig. 6 is a perspective view of the valve housing which is embodied in the modified form of the invention shown in Fig. 5.

50 A preferred form of the new nonrefillable bottle closure is shown in Figs. 1 to 4, inclusive, is therein generally indicated at 10, and is shown as being attached or coupled to the neck 11 of a bottle of conventional design; this coupling being effected by means of a coupling ring 12 which has an upper end portion 13 embedded in the wall of the closure housing or casing 14. This coupling ring 12 also has a convexly inwardly extending bead 15 which is formed in, and projects into, a correspondingly shaped groove 16 which is formed in the neck 11 of the bottle. This coupling arrangement may, of course, be varied but the form of the same shown is well suited for the purpose intended.

60 The closure casing 14 has an internally threaded open upper end 17 and detachably attached to the interiorly threaded neck 17 of the same is a pouring outlet 18 in which a closure plug 19 may be inserted. However, other types of caps, corks or stoppers may be used, if desired.

65 The preferred form of the new nonrefillable closure which is shown in Figs. 1 to 4, inclusive, includes a valve housing 20 which is provided, at its normally lower end, with an inlet opening 21; this valve housing 20 also being provided with a valve seat 22 which is formed, in effect, as the axially inner peripheral wall of the inlet opening 21.

70 It will be noted (Figs. 1 and 4) that in order to

75 mount the valve housing 20 in position of use the same is provided with a peripheral flange 23 which is mounted on the upper edge of the bottle neck 11, this flange 23 being partially inserted into a groove 24 which is formed in the wall of 5 the closure casing 14.

80 Arranged in the valve housing 20, and normally disposed upon the valve seat 22, is a valve element 25, and normally urging this valve element 25 into closed position is a ball 26 which is preferably non-metallic. The ball 26 is confined in position of use by a ball-retaining cage, which is generally indicated at 27, and which, in effect, forms an extension of the valve housing 20, this cage 27 including a peripheral flange 28 which, 15 in use, is mounted upon a plurality of upward extensions or pegs 29 which are formed as a part of the wall of the valve housing 20.

85 The body of the valve housing 20 is, generally, cylindrical in shape, and it has on its inner surface a series of circumferentially spaced ribs 28a in which the valve element 25 is guided.

90 The ball-retaining cage 27 includes a substantially frusto-conically shaped upper end portion which includes a transverse top or end wall 30 and an inclined upper side wall 31.

95 It will be noted that in the present invention the main axis and center line of the closure casing 14, outlet opening 22, and ball-retaining cage 27 are inclined at an angle of approximately 35° from the main axis and center line of the bottle neck 11, valve housing 20, valve element 25, and inlet opening 21, and that the main axis and center line of the valve housing 20 and valve element 25 are coincident with, and extend 35 parallel to, the main axis and center line of the bottle neck 13 and the body of the bottle. It will also be noted that the side wall 31 of the ball-retaining cage 27 is inclined at an angle of approximately 30° from the main axis and center line of the valve housing 20 and bottle neck 14, and that the inner surface 33 (Fig. 2) of the side wall of the ball-retaining cage 27 is inclined at an angle of five degrees (5°) from the horizontal axis and center line of the valve housing 20, valve element 25, and bottle neck 11 when the latter is disposed in horizontal or pouring position (as in Fig. 2).

100 Formed in the side wall 32 of the closure casing 14, on the inner surface thereof, is a series of 50 ribs 34 which space the flange 28 of the ball-retaining cage 27 from the inner surface of the closure casing 14 so that liquid may pour between the ribs 34.

105 The operation of the preferred form of the invention, which is shown in Figs. 1 to 4, inclusive, is as follows: When the bottle and its neck 11 are in their normal or upright and vertical position (as in Fig. 1) the ball 26 rests on the valve element 25 and keeps the latter in engagement with its seat 22, thus closing the inlet opening 21; however, in order to pour liquid from the neck 11 of the bottle on which the preferred form of the new closure shown in Figs. 1 to 4, inclusive, is mounted, it is merely necessary to turn the same through ninety degrees (90°), that is, from the upright or vertical position in which it is shown in Fig. 1 into the horizontal position in which it is shown in Fig. 2, whereupon the ball 26 will run out of the valve housing 20 into the ball-retaining cage 27 and thence down onto the inclined lower surface 33 of the side wall of the same, thereby allowing the valve 25 to slide down the valve housing 20 and into open position, whereupon liquid will pour from 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 8455 8460 8465 8470 8475 8480 8485 8490 8495 8500 8505 8510 8515 8520 8525 8530 8535 8540 8545 8550 8555 8560 8565 8570 8575 8580 8585 8590 8595 8600 8605 8610 8615 8620 8625 8630 8635 8640 8645 8650 8655 8660 8665 8670 8675 8680 8685 8690 8695 8700 8705 8710 8715 8720 8725 8730 8735 8740 8745 8750 8755 8760 8765 8770 8775 8780 8785 8790 8795 8800 8805 8810 8815 8820 8825 8830 8835 8840 8845 8850 8855 8860 8865 8870 8875 8880 8885 8890 8895 8900 8905 8910 8915 8920 8925 8930 8935 8940 8945 8950 8955 8960 8965 8970 8975 8980 8985 8990 8995 9000 9005 9010 9015 9020 9025 9030 9035 9040 9045 9050 9055 9060 9065 9070 9075 9080 9085 9090 9095 9100 9105 9110 9115 9120 9125 9130 9135 9140 9145 9150 9155 9160 9165 9170 9175 9180 91

the neck 11 of the bottle, through the inlet opening 21, into and through valve housing 20, then into the closure casing 14, thence between the ribs 34 and the flange 28 of the ball-retaining cage 27, and finally out of the closure casing 14 by way of the outlet opening 32a. It will be noted, however, that as soon as the neck 11 of the bottle, with the closure 10 attached thereto, is tilted slightly upwardly (clockwise, Fig. 2), the ball 26 will run back down the lower surface 33 of the side wall of the ball-retaining cage 27 (left to right, Fig. 2) and in so doing will engage the valve element 25 and move the latter back into closed position.

15 In the use of the closure which is shown in Figs. 1 to 4, inclusive, the outlet member or pouring throat 18 which is arranged in the outlet end of the closure casing 14 prevents dribbling of the contents of the bottle during and after the pouring operation and since the present closure is especially adapted and intended for use in conjunction with liquor bottles this feature of preventing dribbling and loss of the liquid is of very considerable importance.

20 25 A modified form of the present invention is shown in Figs. 5 and 6 and is generally indicated at 35, and this form of the invention is very similar to the form which is shown in Figs. 1 to 4, inclusive, except that the ball retaining cage 36 which is embodied in the same is slightly different from the cage 27, in form. This difference resides in the fact that the ball-retaining cage 36 has a vertically extending side wall 37 which intersects the angular upper side wall 33 of the said cage to form an angle 39 whereas the upper side wall 34 of the ball-retaining cage 27 does not have this angle which may at times act as a retarding trap for the ball 26; that is, when the modified form of the invention shown in 30 Figs. 5 and 6 is held in horizontal or pouring position, the ball tends to lie in the angle 39 which slows up the movement of the ball 40 back into engagement with the valve element 41, thus preventing the ball 40 from moving quickly 35 back into position to close the valve 41 when the closure 35 is tilted upwardly from horizontal pouring position and necessitating that the closure 35 and the bottle neck 42 on which it is mounted must be tilted upwardly through a greater angle than is necessary in the preferred 40 form of the invention shown in Figs. 1 to 4, inclusive, in order to close the valve. It will thus be seen that this angle 39 tends to reduce the sensitivity of the valve and to slow up the action 45 of the same during the closing operation.

50 Otherwise, however, the modified form of the closure shown in Figs. 5 and 6 is the same as the preferred form shown in Figs. 1 to 4, inclusive.

55 While I have illustrated and described preferred embodiments of my invention it is to be understood that these are capable of variation and modification and I therefore do not wish to be limited to the precise details set forth but desire to avail myself of such changes and alterations as fall within the scope of the following 60 claims.

I claim:

1. A nonrefillable bottle closure comprising, a closure casing adapted to be mounted upon the neck of a bottle and having an outlet opening, the main or longitudinal axis and center line of the said closure casing being inclined at an acute angle from the vertical axis and center line of the bottle neck when the said closure casing is mounted thereon, a valve housing in the

said casing and having a liquid-conducting passage therethrough, a weight-retaining cage upon said valve housing, a valve member in the said valve housing, a weight in the said cage and the said weight normally urging the said valve member into position to close the said liquid-conducting passage, said weight-retaining cage including a wall inclined downwardly from its inner end toward its outer end at an acute angle from the horizontal axis of said bottle neck 10; when said bottle neck is in a substantially horizontal position, and said wall being adapted to support the said weight thereon when the said bottle neck is in a substantially horizontal position. 15

2. A nonrefillable bottle closure comprising, a closure casing adapted to be mounted upon the neck of a bottle and having an outlet opening, the main or longitudinal axis and center line of the said closure casing being inclined at an angle 20 of approximately 35° from the vertical axis and center line of the bottle neck when the said closure casing is mounted thereon, a valve housing in the said casing and having a liquid-conducting passage therethrough, a weight-retaining cage and the said weight normally urging in the said valve housing, a weight in the said cage and when the said weight normally urging the said valve member into position to close the said liquid-conducting passage, said weight-retaining cage including a wall inclined downwardly from its inner end toward its outer end at an acute angle from the horizontal axis of said bottle neck when said bottle neck is in a substantially horizontal position, and said wall 30 being adapted to support the said weight thereon when the said bottle neck is in a substantially horizontal position. 35

3. A non-refillable bottle closure comprising, a closure casing adapted to be mounted upon the neck of a bottle and having an outlet opening, 40 a valve housing in the said casing and having a liquid-conducting passage therethrough for conducting liquid from the said bottle neck to the said outlet opening of the said closure casing, 45 a valve in the said valve housing, a ball-retaining cage arranged upon the said valve housing, a ball in the said cage, and the said ball normally urging the said valve into position to close the said liquid-conducting passage, the main or longitudinal axis and center line of the said closure casing, outlet opening, and ball-retaining cage being inclined at an acute angle from the vertical axis and center line of the bottle neck when the closure casing is mounted thereon and the main or longitudinal axis and center line of the said valve and valve housing being coincident with the vertical axis and center of the said bottle neck, the said ball-retaining cage including a side wall having an inner surface inclined at an acute angle from the horizontal axis and center line of the bottleneck, when the latter is in horizontal position and the said closure is mounted thereon, and in a direction toward the said outlet opening. 55

4. A non-refillable bottle closure comprising, a closure casing adapted to be mounted upon the neck of a bottle and having an outlet opening, a valve housing in the said casing and having a liquid-conducting passage therethrough for 70 conducting liquid from the said bottle neck to the said outlet opening of the said closure casing, a valve in the said valve housing, a ball-retaining cage arranged upon the said valve housing, a ball in said cage, and the said ball normally 75

- urging the said valve into position to close the said liquid-conducting passage, the main or longitudinal axis and center line of the said closure casing, outlet opening, and ball-retaining cage being inclined at an acute angle from the vertical axis and center line of the bottle neck when the closure casing is mounted thereon and the main or longitudinal axis and center line of the said valve and valve housing being coincidental with the vertical axis and center of the said bottle neck, the said ball-retaining cage including a side wall having an inner surface inclined at an angle of approximately five degrees (5°) from the horizontal axis and center line of the bottle neck, when the latter is in horizontal position and the said closure is mounted thereon, and in a direction toward the said outlet opening.
5. A nonrefillable bottle closure, comprising a closure casing adapted to be attached to a bottle and having an outlet opening, a valve housing in the said casing having an inlet opening at its lower end and provided with an outlet into the said closure casing, a valve member in the said valve housing, a ball-retaining cage upon said valve housing, a ball in said ball-retaining cage normally urging the said valve member into closed position, said weight-retaining cage including a wall inclined downwardly from its inner end toward its outer end at an acute angle from the horizontal axis of said bottle neck when said bottle neck is in a substantially horizontal position, and said wall being adapted to support the said weight thereon when the said bottle neck is in a substantially horizontal position.
6. A nonrefillable bottle closure, comprising a closure casing having an outlet opening, a valve housing in the said casing having an inlet opening at its lower end and provided with an outlet into the said closure casing, a valve in the said valve housing, said valve housing having a ball-retaining cage thereon, a ball in the said cage and the said ball normally urging the said valve into closed position, the main axis and center line of the said valve, valve housing, and inlet opening being coincidental with each other and the main axis and center line of the said closure casing, outlet opening, and ball-retaining cage being coincidental with each other and inclined at an acute angle from the vertical axis and center line of the said valve, valve housing and inlet opening, the said ball-retaining cage including a side wall inclined downwardly at an acute angle from the horizontal when the said closure is disposed in horizontal or pouring position.
7. A nonrefillable bottle closure, comprising a closure casing having an outlet opening, a valve housing arranged within the said closure casing and having an inlet opening at its lower end and provided with an outlet into the said closure casing, a valve in the said valve housing, a ball-retaining cage on the said valve housing, and a ball in said cage normally urging the said valve into closed position, the main axis and center line of the said valve, valve housing, ball-retaining cage and inlet opening extending at an acute angle relative to the main axis and center line of the said outlet opening and closure casing, said ball-retaining cage including an annular side wall inclined at an angle of approximately thirty

degrees (30°) from the main axis and center line of the said valve, valve housing, and inlet opening.

8. A nonrefillable bottle closure, comprising a closure casing having an outlet opening, a valve housing arranged within the said closure casing and having an inlet opening at its lower end and provided with an outlet into the said closure casing, a valve in the said housing, a ball-retaining cage on the said valve housing, a ball in the said cage and the said ball normally urging the said valve into closed position, the main axis and center line of the said closure casing, outlet opening and ball-retaining cage being coincidental with each other and extending at an acute angle from the main axis and center line of the said valve, valve housing and inlet opening, the said valve housing having upwardly extending projections formed on the upper surface thereof, said projections extending axially of the said valve housing and being spaced circumferentially therearound and having the said ball-retaining cage mounted thereon.

9. A nonrefillable bottle closure, comprising a closure casing having an outlet opening, a valve housing in the said casing having an inlet opening at its lower end and provided with an outlet into the said closure casing, a valve in the said valve housing, a ball-retaining cage in the said closure casing, and a ball in the said cage normally urging the said valve into closed position, said valve housing having a series of circumferentially spaced projections on the upper surface thereof, said ball-retaining cage having a peripheral flange at its lower end and the said flange being mounted upon the said projections.

10. A nonrefillable bottle closure, comprising a closure casing having an outlet opening, a valve housing in the said casing having an inlet opening at its lower end and provided with an outlet into the said closure casing, a valve in the said valve housing, a ball-retaining cage in the said closure casing, and a ball in the said cage normally urging the said valve into closed position, said valve housing having a series of circumferentially spaced projections on the upper surface thereof, said ball-retaining cage having substantially the form of a truncated cylinder, and said ball-retaining cage having a peripheral flange at its lower end and the said flange being mounted upon the said projections.

11. A nonrefillable bottle closure, comprising a closure casing having an outlet opening, a valve housing in the said casing having an inlet opening at its lower end and provided with an outlet into the said closure casing, a valve in the said valve housing, a ball-retaining cage in the said closure casing, and a ball in the said cage normally urging the said valve into closed position, said valve housing having a series of circumferentially spaced projections on the upper surface thereof, said ball-retaining cage having a peripheral flange at its lower end and the said flange being mounted on the said projections, the said ball-retaining cage having substantially the form of a truncated cylinder and including a side wall having a substantially straight lower portion and an end and the upper portion extending at an angle relative to the said lower portion.
